(57) **CLAIM**

The ornamental design for a mesh gusset for pillow, as shown and described.

DESCRIPTION

FIG. 1 is a top plan view of a mesh gusset for pillow, the bottom plan view being identical thereto;

FIG. 2 is a right side elevational view thereof, the left side elevational view being identical thereto; and,

FIG. 3 is a front elevational view thereof, the rear elevational view being identical thereto.

The broken line showing of FIGS. 1-3 is included for the purpose of illustrating only and forms no part of the claimed invention.

1 Claim, 2 Drawing Sheets

FIG. 1

FIG. 2

FIG. 3
